[57] CLAIM

The ornamental design for a chair, as shown and described.

DESCRIPTION

FIG. 1 is a top plan view of a chair showing my design; FIG. 2 is a front elevation of the chair in FIG. 1; FIG. 3 is a rear elevation of the chair of FIGS. 1 and 2; FIG. 4 is a side elevational view; and, FIG. 5 is a rear perspective view thereof. The side of the chair not shown is a mirror image of the side shown in FIG. 4.

FIG. 4
